UNITED STATES PATENT OFFICE.

HARRY S. CORNISH, OF NEW YORK, N. Y.

DESIGN FOR A LIQUID-DISPENSING KEG.

No. 38,891.

Specification for Design.

Patented Nov. 19, 1907.

Application filed August 6, 1907. Serial No. 387,362. Term of patent 7 years.

To all whom it may concern:

Be it known that I, HARRY S. CORNISH, a citizen of the United States, and a resident of the city of New York, borough of Manhattan, county of New York, and State of New York, have invented a new, original, and ornamental Design for a Liquid-Dispensing Keg, shown in the accompanying drawings, wherein the figure is a front elevation of the keg.

I claim;

The ornamental design for liquid dispensing keg as shown.

HARRY S. CORNISH.
